UNITED STATES PATENT OFFICE.

JOSEPH A. McCORMICK, OF CHICAGO, ILLINOIS.

FLUSH VALVE.

Application filed August 28, 1922. Serial No. 584,659.

To all whom it may concern:

Be it known that I, JOSEPH A. McCORMICK, a citizen of the United States, residing at Chicago, in the county of Cook and 5 State of Illinois, have invented a certain new and useful Improvement in Flush Valves, of which the following is a full, clear, concise, and exact description, reference being had to the accompanying drawings, forming a part of this specification.

My invention relates to valves and more particularly to flush valves.

It is common to control the opening of this type manually and to provide for an 15 automatic shut-off. During the flushing period, a predetermined amount of water should flow at a certain rate to the vessel to be flushed. In order to secure this result it is desirable to maintain the above predetermined flow of water for a desirable 20 period of time. This is commonly accomplished by arranging a timing member within the valve body, so that after the flow of a certain amount of water through the 25 valve, the valve automatically closes. It is common to employ a pressure operated member and a chamber arranged to receive a predetermined charge which accumulates slowly therein through an orifice in order 30 to effect the automatic shut-off properly. In order to be able to make the valve and co-operating parts of relatively small dimensions, it is necessary to make the chamber small. This means that the rate of flow 35 into the chamber must be small, but it must be certain.

The matter of securing a predetermined rate of flow through a small orifice has 40 presented practical and difficult problems. Foreign substances in the water tend to clog this orifice and consequently destroy the desired timed relation in the operation of the valve. Through one of the features of my invention this difficulty has been overcome by the provision of means for permitting a reduced flow into the chamber through a metering orifice, protected by a strainer having a multitude of orifices all smaller than the metering orifice. The assembly of the screen and orifice plate or diaphragm in the moving piston is also novel 50 as will be set forth in detail later.

A further object of my invention is to provide an improved form of manual control mechanism. So far as I am aware, the 55

spring supporting the control has heretofore been placed within the valve body where it is subject to corrosion. In the present arrangement, I have overcome this difficulty by disposing the spring outside of 60 the valve body and providing an improved form of cup leather packing or gasket to prevent leakage between the control valve stem and valve body.

A further object is to provide positive 65 and sufficient means for refilling the bowl after flushing. After the flushing has been completed, the flow is diminished suddenly to a point where it is not sufficient to supply the full cross section of the trap of the 70 closet bowl being flushed. The siphoning action will then cease in time to permit the water which is last discharged into the bowl to remain in the bowl. The bowl proper will thus be refilled and a seal provided 75 to prevent backward flow of the sewer gases.

In order to apprise those skilled in the art how to construct and practice my invention I shall now describe one embodiment thereof in connection with the accompanying drawings, in which:

Figure 1 is a vertical sectional view of a flush valve embodying my invention; and Fig. 2 is a side view of the same.

The flush valve embodying my invention 85 is particularly designed for use in connection with water closets where the operation of the valve should preferably constitute two distinct actions, the first being to flush the bowl, and the second to break off siphoning and thereafter furnish sufficient water to lie in the trap to serve as a seal against backward flow of sewer gases.

Consequently, the valve 1 shown in the drawings is designed to provide a sudden 95 rush of water through the outlet opening 9, and thereafter diminish the flow to interrupt the siphoning action and then slowly discharge water until a water seal is formed in the bowl of the water closet.

The body of valve 1 is provided with a chamber or cylinder 4 having at one end the outlet opening 9. An outlet chamber 5 lies between opening 9 and inlet chamber 4 and connects with the opposite end of the valve by a by-pass 6. The valve body is formed with an annular vertical flange 31 internally threaded for receiving the renewable valve seat ring 32. A main valve member 33 carries a yieldable valve face 34 105 110

adapted to seat upon the valve seat ring 32. This valve closes off communication between inlet chamber 4 and outlet chamber 5.

Tail piece 10 connects with outlet opening 5 9 by suitable union connection 8.

Valve 33 is preferably formed integral with a horizontal plate 35 having a central bore and spaced from said plate by a plurality of vertical web members 36, between 10 which water passes to a port or orifice 37 provided in a diaphragm 38, the central part of which is formed into a cup. The cup 38, together with a strainer 39, comprises part of a piston 40, operating in chamber 4.

15 Water is admitted in to the valve body through inlet opening 16 disposed adjacent to but below the piston, and by virtue of its position the opening 16 will never be closed off by the piston 40. The screen or strainer 20 39 is so placed with respect to the water inlet 16 and discharge port of the valve 33 that when the valve is opened the inrushing water tends to clean the screen. Water slowly enters the upper part of chamber 4

25 above the piston through port or orifice 37, thus moving the piston slowly downwards to seat the valve 33 upon the seat ring 32. The piston is provided with cup leathers 41 and 42 which maintain a tight fit with the

30 walls of the cylinder. The cups are faced in opposite direction and clamped against each other and to the plate 35. The cup leathers require suitable backing in order to maintain a tight working fit with the 35 surrounding cylinder. The cup or dia-

phragm 38 extends through the cup leathers from the upper side. The flange above the cup 38 is clamped against the margins of the cup leathers holding them in place against the flange 35. The strainer 39 which is also 40 cup shaped, has integral cylindrical walls which nest or telescope with the cylindrical walls of the cup 38. The strainer 39 has a push fit upon the cup 38 and may readily be

45 removed for changing or the like. The control 47 is adapted to nest in the central portion of cup 38 when piston 40 is in upper position. The formation of the diaphragm into cup shape makes possible several ad-

50 vantages. The nesting of the valve 47 and cup 38 allows the cylinder 4 to be made relatively short. The cup 38 permits of an advantageous form of screen and its position in relation to the inrushing water tends to 55 clean it automatically.

A bonnet or head 2 properly secured to the upper part of the valve body is provided with a pocket 3 forming a continuation of by-pass 6, in the main valve body 1. A 60 manually controlled push button bearing a valve 47 controls a port 46 between the cylinder 3 and the exhaust passageway or by-pass channel 6. Each time the push button is depressed, the water trapped in the chamber 4 is discharged to the outlet

chamber. This is accomplished by unseating valve 47 from port 46 in the bonnet 2. Control valve 47, which seats with the internal water pressure, is moved to seat positively by the spring and by the internal 70 water pressure. As soon as the pressure is removed from the push button the valve is free to seat under the influence of return spring 19. This manual control valve assembly comprises a valve stem 50 threaded 75 at the lower end to receive a flanged nut 51, and having a flange 52, between which flange and the nut is confined a yielding rubber valve body 47. Stem 50 threads at its upper end into a button base 21 which carries a 80 retaining ring 24. It will be noted that the ring 24 is threaded on base 21 so that button 26 may be readily replaced if so desired. Ring 24 is flanged to embrace and accommodate the upper convex face of the button. 85 The cylindrical wall 18 about the pocket 3 forms a cylinder and serves to guide the shank 22 of the button base 21. To provide an efficient water joint or packing at this point, an inverted cup leather 60 is secured 90 on stem 50 just below shank 22. The spring 19 for returning the plunger button to upper position is confined between a flange 20 and the button base member 21, and outside the pocket 3. This spring lies outside the wall 95 18 where it is entirely out of contact with the water.

A bonnet cover 30 lies over the bonnet 2, so that its upper part 29 forms a cylinder and protects the spring 19. Retaining ring 24 lies over flange 29 and overhangs the upper edge of the bonnet cover. To prevent the rotation of the plunger when the ring 24 is to be turned on its threads, a pin 61 is embedded in the base member and projects 100 to engage in slot 62 cut in the upper edge of wall 18. The pin 61 and slot 62 may be engaged by depressing the button against the 105 spring 19.

The operation of the valve is as follows: 110

Assuming that the cylinder 4 has been properly charged with water and that the other mechanism is ready to be put into operation. The control valve 47 is then unseated from the port 46 by the button 26 being manually depressed. The internal water pressure will force the piston upwardly, pushing the water trapped in cylinder 4 out through port 46 and into the by-pass 6; the valve 33 will then be lifted from its seat because of the difference in areas of piston 40 and bore of valve 33. As soon as the control valve 47 is cracked open the main valve tends to unseat very easily. As long as the control valve 47 remains unseated, the piston 40 will stay in its upper position. However, when cylinder 4 is again closed on the side of the control valve, piston 40 gradually lowers and seats the main valve 33. The pressures on opposite sides 120 125 130

of the piston 40 are equal when valves 33 and 47 are closed. Refilling of cylinder 4 starts as soon as the valve 47 is returned to its seat 46.

5 A guide is mounted on the underside of main valve 33 and is formed with a plurality of spaced guide ribs 66.

The refill arrangement consists of a plug or boss 65 inserted below the valve face 34. 10 This plug or boss is of slightly smaller diameter than the bore of surrounding seat ring 32. This recessed boss overlaps into the guide ribs, so when its lower edge enters the seat bore and the full water supply 15 stops, a reduced water supply may still flow through the seat opening all as predetermined by this refill arrangement. As the main valve 33 seats slowly the water flow decreases suddenly because of the entry of 20 the solid portion 65 into the opening in the valve ring 32 and this breaks the siphoning action in the bowl, and finally allows a water seal to form in the trap and bowl proper. Final closing off occurs when the 25 valve face 34 rests on the valve seat ring 32.

The openings in strainer 39 are considerably smaller than port 37, so whatever passes through the strainer will not clog the port. Furthermore, the strainer 39 is large 30 enough to allow sufficient water to pass to satisfy port 37, although the strainer may be partly or almost fully clogged.

The particular construction of the push button is unique and has many advantages, 35 largely due to the location of the spring 19. Being on the outside of the water seal, the spring 19 will not be subject to the action of the water as in devices of the prior art where the spring lies on the inside of the 40 valve body. The bonnet cover 30 and ring 24 house the spring and protect it against damage.

As shown, the valve 47 is formed of rubber of a size substantially that of half of a 45 "Fuller" ball. Thus, for renewing the valve 47 a Fuller ball may be cut into half and employed.

Obviously a lever instead of a pushbutton 50 may be employed to actuate starting valve 47.

I do not intend to limit myself to the details herein shown.

I claim:—

1. In combination, a cylinder, a head for 55 said cylinder, a fluid operated piston in said cylinder, a control valve in said head, a plunger push button connected with said control valve and carried as a unit on said head, a cover extending over said head and part of said push button, a removable ring 60 on said push button for permitting axial movement of said cover to uncover said head, and means for removing said head whereby access to said control valve is had.

65 2. In combination, a cylinder, a fluid op-

erated piston in said cylinder, a main valve adapted to be seated by said piston, a second cylinder, a push button guided in said second cylinder and having a connection with a control valve, a removable ring having rotative movement relative to said push button, and means on said second cylinder and said push button engaging with each other to prevent rotation of said push button when said ring is moved relative to said push button. 70 75

3. In combination, a cylinder, a fluid operated piston in said cylinder, an inlet and an outlet opening at one end of said cylinder, a main valve operated by said piston for closing off communication between said 80 openings, a control valve at the other end of said cylinder, a cup carried by said piston, said cup having an orifice therein, a second cup lying over said first cup on the side adjacent to said openings, said second cup having holes therein of smaller size than said orifice in said first cup. 85

4. In combination, a cylinder, a fluid operated piston in said cylinder, an inlet and an outlet opening at one end of said cylinder, 90 a main valve operated by said piston for closing off communication between said openings, the other end of said cylinder being closed off by a control valve when seated, said piston comprising a pair of cup leathers 95 with a metal cup overhanging from one side of said piston, an annular flange on said cup for re-enforcing said cup leathers on said control valve side, a connection between said main valve and said piston having a similar 100 re-enforcing extension thereon for the other side of said cup leathers, and an orifice in said overhanging portion of said cup.

5. In combination, a cylinder, a fluid operated piston in said cylinder, an inlet and 105 an outlet opening at one end of said cylinder, a main valve for closing off the communication between said openings, said valve controlled by said piston, a control 110 valve at the other end of said cylinder, means for operating said control valve, said piston comprising cup leathers re-enforced by members of greater rigidity than said cup leathers, one of said members being cup shaped in the center thereof for clearing said 115 control valve when said piston is adjacent to said control valve.

6. In combination, a cylinder, a fluid operated piston in said cylinder, an inlet and an outlet opening at one end of said cylinder, 120 a main valve for closing off the communication between said openings, said valve controlled by said piston, said piston comprising cup leathers re-enforced by members of 125 greater rigidity than said cup leathers, one of said members being cup-shaped in the center thereof, said member having an orifice in said cup portion, a strainer for said orifice, said strainer extending substantially 130 in the path of the flow of the fluid entering

said cylinder through said inlet opening when said piston is in lower position.

7. In combination, a cylinder, a head for said cylinder, a fluid operated piston in said cylinder, a control valve in said head, a second cylinder in axial alignment with first said cylinder, a push button connected with said control valve, said connection extending through said second cylinder, a spring between said push button and said second cylinder, a covering lying over said head, a removable ring on said head and overlying the upper portion of said cover, said spring being disposed within said cover and said ring.

8. In combination, a cylinder, a piston in said cylinder, said piston comprising a pair of cup leathers faced in opposite direction

and clamped against each other, a plate against one of said cup leathers, the middle portion of said plate being depressed into a cup and extending through said cup leathers, said cup provided with an orifice for permitting fluid to flow through said piston.

9. In combination, a cylinder, a piston in said cylinder, said piston comprising a pair of cup leathers faced in opposite direction, a plate against one of said cup leathers, the middle portion of said plate being depressed into a cup for extending through said cup leathers, said cup having an orifice therein, and a strainer cup having a push fit between the walls of said cup and said cup leathers.

In witness whereof, I hereunto subscribe my name this 7 day of August, 1922.

JOSEPH A. McCORMICK.
